UNITED STATES PATENT OFFICE

2,602,431

BOILER CONSTRUCTION

James K. Dukas, Edwardsville, Pa.

Application March 3, 1947, Serial No. 731,948

1 Claim. (Cl. 122—231)

2

This invention relates to furnaces, boilers, and the like, and has for one of its objects the production of a simple and efficient means for facilitating the fastening of the sections of boilers, furnaces, and the like, together.

Another object of this invention is the production of a simple and efficient means for facilitating access to the securing means which fastens the sections of the furnace or boiler together.

Other objects and advantages of the invention will appear throughout the following specification and claim.

In the drawings:

Figure 1 is a front elevational view of the furnace, boiler, or the like;

Figure 2 is a side elevational view illustrating the manner in which a plurality of furnace or boiler sections are assembled;

Figure 3 is an enlarged fragmentary side elevational view of a front and rear section assembled, certain parts being shown in section;

Figure 4 is a fragmentary transverse sectional view through the top portion of one of the furnace or boiler sections;

Figure 5 is a side fragmentary elevational view illustrating a front and rear section secured together, illustrating the location of the feeder pipes for the water jacket;

Figure 6 is a rear elevational view of the front section;

Figure 7 is a front elevational view of the rear section;

Figure 8 is a fragmentary sectional view illustrating the securing means for anchoring the sections of the furnace or boiler together;

Figure 9 is a modified form of the securing means illustrated in Figure 8;

Figure 10 is a vertical sectional view taken on line 10—10 of Figure 6.

By referring to the drawings, it will be seen that 10 designates the furnace or boiler, which may be formed of a front section 11, a rear section 12, and an intermediate section 13, as shown in Figure 2, if desired. Other intermediate sections may be employed to increase the capacity of the furnace or boiler, as occasion may demand. For the purpose of describing the invention, the description will be directed to a furnace or boiler having a front and a rear section, although it should be understood that any number of sections may be used without departing from the spirit of the invention.

Fuel-feeding hoppers 14 preferably are supported above the furnace or boiler 10, as shown in Figures 1 and 2, and feed pipes 15 convey fuel

from the hoppers 14 to the fire-box of the furnace or boiler. Suitable operating levers 16 operate the valve 17 for controlling the delivery of fuel from the hoppers 14 to the fire-box.

Each section of the furnace or boiler 10 is provided with a water jacket 18 or compartment within which water and steam is contained during the operation of the furnace or boiler. The sections of the boiler may be of the conventional design having a depending hollow central partition 19. A suitable sealing gasket 20 of the conventional type is interposed between the sections of the furnace or boiler 10. The sections 11 and 12 are provided with abutting walls 21 and 22 respectively, between which the sealing gasket 20 fits. Securing elements 23 pass through the abutting walls 21 and 22 and the gasket 20, at selective intervals, and threaded rings 24 are threaded upon opposite ends of the securing elements 23 and engage the inner faces of the respective abutment walls 21 and 22 to firmly anchor the abutment walls together in sealed relation, as shown in detail in Figure 8. The outer side walls 25 and 26 of the sections of the furnace or boiler are provided with access ports 27 which are normally covered by cover plates 28 and are provided with suitable sealing gaskets to provide a water-tight seal. Suitable securing elements, screws, bolts or the like, anchor the plates 28 in position. The ports 27 are formed at selected locations where access may be had to the interior of the water jackets of the various sections to fasten the securing elements 23 and the bushings 29 and 30 which provide communicating ports between the sections at the top of the water jackets. The bushing 29 provides a communicating steam port and the bushing 30 provides a communicating water port. The bushings 29 and 30 may be secured in a manner illustrated in Figures 8 or 9 and may be of the same construction except as to size, and are hollow to permit a free flow of water or steam between the water jackets of the abutting sections of the furnace or boiler.

I preferably provide enlarged access ports or openings 31 in the outer side walls of the sections which extend vertically and over a sufficient area so that access may be had to all parts for installation of the circulating or communication pipes 32, and for fastening the securing elements 23 and rings 24 thereof. A cover plate 33 closes each opening 31 and carries a sealing gasket 34. Suitable securing elements 35 anchor the plates 33 in a closing position. The pipes 32 are preferably threaded, as at 36, into the side walls of

the partition 19 and are secured to the inner side walls 37 of the outer water jacket by the conventional sweating process. As stated above, access may be had to these pipes 32 through the openings 31 when the plates 33 are removed.

As shown in Figure 9, a securing element 38 may replace the securing element or elements 23. This securing element 38 is threaded into one abutment wall 22^a and carries a threaded ring 39 which is threaded upon the opposite end of the element 38 to overlap the inner face of the adjacent wall to clamp the walls 22^a and 21^a together and clamp the gasket 20^a therebetween.

The rear section 12 is provided with flues 40 having the bottom edges thereof terminating at an elevation above the bottom end of the partition 19 thereof to cause the heating fumes to pass upwardly through the section 11 between the pipes 32 through the flues 40 and downwardly between the pipes 32 of the rear section 12 and out through the stack-communicating opening 41 formed in the rear wall at the bottom of the section 12. Baffle plates 42 are placed in the section 11, as shown in Figure 3 to provide a circuitous circulation of the heating fumes in their upward path of movement. Similar baffle plates may be provided in all sections when desired without departing from the spirit of the invention.

It will be noted that I provide a large cover plate 33 and a large aperture 31 to permit access to the securing elements 23 and access to the pipes 32 in the section 11, whereas in section 12 I provide a plurality of ports and a plurality of cover plates 43 for this purpose. The size and number of ports and plates may be varied to suit the type and size of section employed.

From the foregoing description, it should be noted that an efficient heating unit has been produced to obtain a maximum efficiency from a heating standpoint, as well as in the efficiency of assembling the sections of the furnace or boiler for proper operation. The passage of the heating fumes over a maximum heating surface and in a circuitous passage will produce a maximum heating capacity. The assembly of sections of a boiler or furnace of the general type to which this invention relates has been a difficult task but the arrangement of the ports and securing elements herein described and illustrated in the drawing will greatly facilitate the assembly of said sections.

As shown in Figure 5, water feeder pipes 42 communicate with the water jacket of the section 11 in the conventional manner. It should be noted that the heating unit in the nature of a furnace or boiler 18 is provided with two clean-out doors 45 and a lock-in fire door 46 in the furnace front.

Having described the invention, what is claimed as new is:

A heating unit of the class described comprising a plurality of sections, each section having a water jacket, the adjacent sections having flat abutment walls provided with inner faces, a flat sealing gasket fitting between the abutment walls of the sections, said abutment walls having registering apertures, hollow securing elements passing through said registering apertures of the abutment walls and through the gasket to provide communication between the sections of the unit, said securing elements having externally threaded opposite ends, means engaging the opposite threaded ends of the securing elements for securely fastening and sealing the flat abutment walls of said sections against said gasket to provide a water-tight seal therebetween, said sections having side walls, and said side walls having normally closed access means adjacent the securing elements to facilitate access to the securing elements.

JAMES K. DUKAS.
